UNITED STATES PATENT OFFICE.

JOHN A. DICKERMAN, OF BRIDGEPORT, CONNECTICUT, ASSIGNOR TO REMINGTON ARMS COMPANY, INC., A CORPORATION OF DELAWARE.

MUSHROOMING BULLET.

Application filed February 4, 1922. Serial No. 534,176.

This invention relates to mushrooming bullets and has for an object the provision of a bullet having superior accuracy and mushrooming qualities.

5 It is well known that ordinary metal jacketed bullets are unsatisfactory for large game shooting because they will penetrate through animal tissue without causing much damage or shock to the game because a comparatively 10 small amount of its kinetic energy is absorbed in the game. For this reason it has become customary to use what is known as the "soft point" bullet, the body of which is jacketed and a small amount of the core material, generally lead, is exposed at the point. The base or heel of the bullet is generally completely jacketed over. Such bullets mushroom easily upon striking animal tissue and cause considerable expansion of the 20 point, approximately the forward half of the bullet, thus taking on a mushroom shape, from which the name of this general class of bullets is derived.

This type of construction gave most excellent results with the relatively blunt nosed bullets in general use prior to about 1905. When the so called "spitzer" bullet was developed, it was very quickly adopted by nearly all countries for military purposes,

30 on account of its low trajectory and superior accuracy. A considerable demand immediately arose for bullets of the "spitzer" type adapted for big game hunting. Full jacketed bullets of the "spitzer" type were 35 particularly poorly adapted for hunting purposes on account of their shape. "Soft point" bullets of this type were therefore provided, but it soon became evident that on account of the long sharp nose, it was

40 necessary to expose a relatively long part of the nose to insure mushrooming, with the result that the soft tip was very liable to injury and was frequently deformed even in the original ammunition box, or in the

45 belt or pocket of the hunter, and more particularly in the magazine of repeating rifles (and especially so in the case of tubular magazine repeating rifles) and when being inserted into the chamber of 50 single shot or repeating rifles. As the slightest deformation of the point will seriously affect the accuracy of the bullet, it was found that such bullets were entirely unreliable and unsatisfactory. Another difficulty which 55 was soon discovered was that the soft exposed

point, under the extremely high acceleration of the bullet produced by the explosion of the propelling charge, had a tendency to flow back while the bullet was passing thru the barrel, resulting in a further deformation and inaccuracy of the bullet.

The provision of a suitable hunting bullet adapted for use in rifles using the "spitzer" type of bullet presented a very serious problem to the solution of which the experts of all the ammunition companies and many others applied themselves. The result has been that many constructions have been proposed, some of which have been patented and have found their way onto the market. One of these was the internal reinforcement of the point as by a wire embedded in the core material. Others contemplated securing a mushrooming effect by forming the point hollow, and others provided a hard wedge-shaped tip intended to cause expansion of the jacket, and another class of bullets of this type had a separate drawn jacket covering the tip of the bullet and attached to the body of the jacket in various ways, the purpose of this construction being to reinforce the point sufficiently to prevent distortion and deformation and yet not prevent mushrooming upon impact.

Most, if not all, of these constructions presented difficulties and disadvantages, either with respect to cost of manufacture or to effectiveness, which it is not necessary to recite here. By the construction hereinafter set forth, a bullet has been provided which, while relatively cheap to manufacture, has very superior mushrooming qualities, while being at the same time sufficiently protected against deformation or distortion. The invention is illustrated in several forms in the attached drawings, wherein Fig. 1 illustrates the invention as embodied in a bullet of the blunt nosed type. Figs. 2 and 3 represent slight modifications. Fig. 4 shows the invention as used in connection with a bullet of the "spitzer" or sharp nosed type. Figs. 5 and 6 illustrate slight modifications thereof. Fig. 7 shows the invention applied to a bullet of the flat nosed variety. Figs. 8 and 9 show slight modifications thereof. Fig. 10 shows the invention embodied in a bullet of the "hollow point" type. Figs. 11 and 12 show slight modifications thereof.

Referring to Fig. 1, the numeral 14 designates the usual body jacket of a bullet

of the general type illustrated, composed of any suitable jacket metal, such as copper or cupro-nickel. As here shown, the jacket extends rearwardly the full length of the bullet and may completely enclose the base or heel of the bullet. The numeral 15 designates the core, which is preferably formed of lead or an alloy containing a large percentage of lead. 16 designates a deformable or collapsible point which may be formed, as in the embodiment shown, by extending the core material forwardly beyond the jacket. Covering said exposed nose 16 and, in the form shown, covering also the entire jacket, is a thin coating of a harder material 17, such as copper, nickel, or tin, or other suitable metal or alloy, preferably applied thereto by electro-deposition or otherwise deposited thereon as by dipping the bullet in a bath of molten plating material. The coating therefore provides an external reinforcing armor for the soft nose and forms a binding connection between the nose and the jacket. It is formed of such a thickness that it will effectively reinforce the soft point against deformation and distortion, while at the same time not being strong enough to interfere materially with mushrooming upon impact. When the reinforcing coating extends to and covers the jacket 14, it is necessary to make the bullet jacket somewhat smaller in diameter than otherwise required, the difference being made up by the thickness of the reinforcing coating.

In Fig. 2 the reinforcing coating 17' extends only as far as the jacket, the exposed soft nose having been made sufficiently smaller so that when the reinforcing coating is applied its outside surface will come flush with the jacket. In Fig. 3 the forward portion of the jacket 14 is swedged into the core, as shown in 14', sufficiently far to compensate for the thickness of the reinforcing coating, so that the outside surface of the coating 17'' comes flush with and forms a continuation of the outside surface of the jacket. The construction of Fig. 4 is very similar to that of Fig. 1 and the reference characters employed are the same as those applied to corresponding parts in Fig. 1. On account of the increased length of the soft point 16, the difficulties encountered in the use of an unprotected deformable or collapsible point in bullets of this type becomes readily apparent, and the effectiveness of the reinforcing coating 17 as a reinforcement for, and protection to, the soft point is more obvious. In this case as in the instance of Fig. 1, the bullet is first made with a subnormal diameter and its diameter brought to normal by the addition of the reinforcing coating 17. Figs. 5 and 6 correspond to 2 and 3, respectively, and it is therefore not deemed necessary to enter in-

to an extensive description thereof. Figs. 7, 8, and 9, correspond respectively with Figs. 1, 2, and 3, the only difference residing in the shape of the point. Fig. 10 illustrates the invention as applied to a hollow point soft nose bullet. The parts correspond with and bear the same reference numerals as in Fig. 1. The nose of the bullet is, however, formed with a substantially axial cavity 18, facilitating mushrooming upon impact. During the deposition process the coating 17 is applied not only to the external parts of the bullet, but also to the internal areas of the cavity 18, as is shown at 19. The coating 19 forms an axial tubular reinforcement for the tip, reinforcing the same against distortion. Figs. 11 and 12 illustrate a hollow point bullet of the type shown in Fig. 10 and in modifications corresponding to Figs. 2 and 3, and a detailed description is not deemed necessary.

It will be seen therefore that the construction above described provides a mushrooming bullet having the excellent mushrooming qualities possessed by the soft point bullet, while at the same time, being sufficiently protected and reinforced to permit of its being carried on the person and used in repeating rifles without suffering such distortion and deformation as to impair accuracy.

It is to be understood also that the invention is not limited to the forms shown as certain elements illustrated therein are not essential to the utility and effectiveness of the invention.

In the appended claims the term "coating" is to be understood to mean a relatively thin covering, deformable on impact with a soft target and placed by electro-deposition or otherwise on a formed projectile, and adhering thereto.

The invention claimed is as follows:

1. In a sharp nosed mushroom bullet tapering to a point at its forward end, the combination with a jacket, a soft core located therein and projecting forwardly beyond the jacket and continuing the lines of the bullet to a relatively sharp point, and a coating of protecting and reinforcing material deposited on and covering said forwardly projecting point and said jacket.

2. In a sharp nosed mushroom bullet tapering to a point at its forward end, the combination with a jacket, a soft core located therein and projecting forwardly beyond the jacket and continuing the lines of the bullet to a relatively sharp point, and a coating of protecting and reinforcing material deposited on and covering said forwardly projecting point.

3. In a sharp nosed mushroom bullet tapering to a point at its forward end, the combination with a jacket enclosing the

- body and heel of said bullet, a soft core located therein and projecting forwardly beyond the jacket and continuing the lines of the bullet to a relatively sharp point, and a 5 coating of protecting and reinforcing material deposited on and covering said forwardly projecting point and said jacket.
4. In a sharp nosed mushroom bullet tapering to a point at its forward end, the combination with a jacket, a soft core located therein and projecting forwardly beyond the jacket and continuing the lines of the bullet to a relatively sharp point, said forwardly projecting point and the forward 10 part of said jacket being formed of subnormal dimensions and a coating of protecting and reinforcing material deposited on and covering said forwardly projecting point and said forward part of said jacket 15 to bring them to normal dimensions.
5. In a mushroom bullet the combination of a bullet body, a forwardly projecting collapsible or deformable point attached to said body and a coating of protecting and reinforcing material deposited on said forwardly 20 projecting point.
6. In a mushroom bullet the combination of a bullet body, a forwardly projecting collapsible or deformable point attached to said body and a coating of protecting and reinforcing material electrically deposited on said forwardly 25 projecting point.
7. In a sharp nosed mushroom bullet tapering to a point at its forward end, the combination with a jacket, a soft core located therein, a forwardly projecting deformable point and a coating of protecting and reinforcing material deposited on said forwardly 30 projecting point.
8. In a sharp nosed mushroom bullet tapering to a point at its forward end, the com- 35
- bination with a jacket, a soft core located therein, a forwardly projecting deformable point and a coating of protecting and reinforcing material electrically deposited on 40 said forwardly projecting point.
9. In a mushroom bullet the combination of a bullet body, a forwardly projecting collapsible or deformable point formed of subnormal dimensions, and a coating of protecting and reinforcing material deposited on 45 said forwardly projecting point.
10. In a mushroom bullet the combination of a bullet body, a forwardly projecting collapsible or deformable point formed of subnormal dimensions, and a coating of protecting and reinforcing material deposited on 50 said forwardly projecting point.
11. In the manufacture of bullets the process of forming the bullet of subnormal dimensions and then depositing thereon a coating of metal to bring said bullet to normal dimensions. 55
12. In the manufacture of bullets the process of forming the point of the bullet of subnormal dimensions and then depositing on said point a coating of metal to bring said point to normal dimensions. 60
13. In the manufacture of bullets the process of forming the bullet of subnormal dimensions and then electrically depositing thereon a coating of metal to bring said bullet to normal dimensions. 65
14. In the manufacture of bullets the process of forming the point of the bullet of subnormal dimensions and then electrically depositing on said point a coating of metal to bring said point to normal dimensions. 70
- In witness whereof I have signed my name hereto this 1st day of Feb. 1922. 75
